UNITED STATES PATENT OFFICE.

ELIJAH D. FULFORD, OF UTICA, NEW YORK, ASSIGNOR OF ONE-HALF TO
J. H. WEBSTER AND PAUL NORTH, OF CLEVELAND, OHIO.

SINGLE-TRIGGER MECHANISM FOR FIREARMS.

SPECIFICATION forming part of Letters Patent No. 704,024, dated July 8, 1902.
Application filed July 24, 1901. Serial No. 69,468. (No model.)

To all whom it may concern:

Be it known that I, ELIJAH D. FULFORD, of Utica, in the county of Oneida and State of New York, have invented certain new and useful Improvements in Single-Trigger Mechanisms for Firearms; and I do hereby declare that the following is a full, clear, and exact description of the invention, which will enable others skilled in the art to which it applies to make and use the same, reference being had to the accompanying drawings, and to the letters and figures of reference marked thereon, which form part of this specification.

The object of my present invention is to provide an improvement in single-trigger mechanisms for double-barrel guns which is simple in construction, free from involuntary operations, and capable of adjustment to enable one or the other of the two barrels to be fired as desired.

Other and further objects of the invention will appear hereinafter.

In the drawings, Figure 1 shows, in partial section in double ordinary size, portions of a gun or firearm embodying my single-trigger mechanism. Fig. 2 is a partial horizontal section, also in double size, of the arm and in part a plan view of the mechanism. Fig. 3 shows in side elevation the trigger and attached parts employed in the construction. Fig. 4 shows in perspective a ratchet or escapement wheel employed in the construction. Fig. 5 shows in plan view the same in connection with attached parts. Fig. 6 shows an escapement-anchor with its pawls or dogs and spring. Fig. 7 shows a section of the devices shown in Fig. 5. Fig. 8 shows details of the adjusting mechanism separated from the other parts of the firearm. Fig. 9 shows other details, being certain of the parts shown in Fig. 8.

Referring to the reference letters and figures in a more particular description, 1 indicates the usual breech-frame of a double-barrel shotgun, which is provided with the upper tang 2 and the lock-plate 3 in the nature of a removable lower tang of the frame. The lock-plate 3 is provided with a stud or post 4, into which is screwed the lower end of the

bolt 5. These parts are as usually found in firearms of the class specified.

The single trigger 6 is pivoted at 7 to a fixed point, preferably on the lock-plate 3. The trigger includes or has attached thereto rigidly an addition or extension 6^a in the nature of a pair of plates, which receive between them the ratchet or toothed wheel 8. The toothed wheel 8 is mounted rotatably upon its journal or bearing 9 in the trigger addition or extension 6^a and is engaged by the jointed escapement-anchor 10, which is mounted on a pivotal pin 11, also supported in the trigger extension 6^a. The ratchet or escapement wheel 8 is provided in either side 6^a with recesses 8^a, which receive in part the adjustable sear-catches 12 and 13. The catches 12 and 13 are capable of a limited swinging movement with reference to the ratchet-wheel, determined by the width of the recess 8^a, and are provided with detents a, which engage in openings and secure the catches against relative movement with the ratchet-wheel except when forcibly moved. The catches 12 and 13 are respectively adapted to engage at suitable times with the sears 14 and 15, which sears are similar, except that they control the firing mechanism of the left and right hand barrels, respectively. The sears are pivoted in the frame or to the lock-plate at 16, and the catch end of the sear is adapted to engage in the usual manner with the hammer 17, pivoted at 16.

19 indicates the hammer-spring.

Secured at one end at b to the trigger extension 6^a is a U-shaped spring 20. The movable end of this spring 20 is secured to a pin c in the ratchet-wheel 8, which pin c extends through a slotted opening d in the plate portions of the trigger extension 6^a. A pair of these springs 20 may be provided upon each side of the trigger extension 6^a, if desired. Such a pair is shown in the plan view in Fig. 2. The escapement-anchor 10 has one of its pallets mounted on the body 95 portion thereof, while the other pallet e is mounted on a hinged or movable portion. The hinging-point of the movable portion is on the main pivot 11 of the anchor, and the movable portion is capable of movement from 100

the position shown in full lines to that shown in dotted lines in Fig. 6. It is held in its normal position by the spring 10. The escapement-anchor 10 is provided with an elongated opening *f*, which receives a fixed stud or pin 21, supported by the fixed arched bar 22 from the frame or trigger plate.

Sear-catches 12 and 13 are respectively connected by connecting-bars 23 and 24 with the downwardly and upwardly extending arms of the rocking part 25. The part 25 is mounted in a movable arm 26, which support is capable of sliding backward and forward in a line substantially parallel with that of the barrel of the gun. The rocking part or sear-adjusting lever 25 has connected to its lower arm the thumb-piece 27, arranged on the outside of the frame in suitable position to be operated in shifting the position of the sear-catches 12 and 13. The usual catch provided in this class of arms, which secures the barrels in closed position to the frame and which is operated by the lever 26 and the shaft 27, is provided with the rear extension or bumper 30, adapted to engage with the part 26, as will hereinafter be more particularly pointed out.

The trigger 6 is provided with a heel-piece 6^b, which has on its upper side a couple of tooth-like projections, as shown. A connecting-rod 35 is provided upon one side of the arm, which at its forward end is pivoted to the hammer at *h* and adjacent to the rear end slides freely through a keeper *g* on the post 4, heretofore mentioned. The connecting-rod 35 is provided with a tooth *j*, adapted to coöperate with one of the teeth on the upper side of the trigger heel-piece 6^b. The connecting-rod to the hammer of the other barrel of the gun is indicated by 36, and this connecting-rod is provided with a tooth *k*, coöperating with the rear tooth on the trigger heel-piece 6^b. This mechanism serves to force the trigger down should the operator fail to release it promptly. The spring 38 is provided and secured on the lower tang or lock-plate 3, which operates on the pin *m*, provided in the trigger, and operates to throw the trigger downwardly when it is released by the operator.

The mechanism for cocking the hammer is not shown, as it is well understood and operates from the barrels when the gun is broken down. When cocked, the hammers are caught by the catch end of the sears, as is usual in such cases. When the trigger 6 is pulled by the operator, the ratchet-wheel 8 is moved upward in connection with the movement of the trigger extension 6^a and the catch 12, engaging with the rear end of the sear 14. The sear is operated to disengage the hammer, which then operates under the influence of the spring 19. As the hammer operates the tooth *j* of the connecting-rod 35 is passed over the tooth on the trigger heel-piece 6^b, which is then in its upper position, and the trigger is forced downwardly. The

anchor of the escapement being held by pin 21, as the wheel 8 is moved up and down the escapement is operated, so as to allow the wheel to rotate one notch under the influence of the spring 20. In this movement the catch 12 is swung out of engagement with the sear 14. Under the influence of the recoil of the gun the operator makes an involuntary pull on the trigger, which again raises the wheel 8, and the escapement operates a second time, the wheel 8 rotating further to a succeeding tooth under the influence of the spring 20. In this last movement the catch 13 comes into position for engagement with the sear 15. The next pull of the trigger, which is a voluntary pull, then is communicated by the catch 13 to the sear 15, and the hammer connected with this barrel of the arm is released. As the ratchet-wheel 8 with the sear-catches 12 and 13 perform the movements last described the connecting-rods 23 and 24, together with the shifting lever 25 and its mounting 26, all move to the left from the position shown in Fig. 1, so that at the conclusion of the three movements described the dependent portion of the mounting 26 is in contact with or close to the bumper 30 on the end of the barrel-release catch heretofore described. When the release-catch is operated by means of the lever 26 and the rocking shaft 27, the bumper 30 moves to the right, as shown in Fig. 1, and forces the mechanism last described into the position shown in full lines in Fig. 1, when the same is reset ready for a repetition of the firing operations. As the mechanism is reset, as described, the ratchet-wheel 8 is forcibly rotated, so that the ratchet-teeth are retracted through under the escapement-anchor 10. This movement would require a rapid vibration of the trigger were it not for the joint in the escapement-anchor heretofore described, which allows the pallet *e* to move with reference to the body of the pallet as it is retracted over the toothed periphery of the ratchet-wheel 8. With the parts in the position in which they are shown in Fig. 1 the arm is arranged to shoot first the left-hand barrel and then the right. This order may be reversed by the operator moving the thumb-piece 27 toward the rear, which, operating through the shifting lever 25 and the connecting-rods 23 and 24, serves to reverse the relative positions of the catches 12 and 13, so that on the first movement of the trigger the catch 13 is in engagement with its sear and the catch 12 comes into operation in due course afterward. When the hammer controlled by sear 15 is operated first, the tooth *k* on the connecting-rod 36 operates to cam the trigger down immediately preceding the involuntary pull before mentioned.

What I claim as new, and desire to secure by Letters Patent, is—

1. In a single-trigger mechanism, the combination of a trigger, an escapement-wheel mounted on the trigger and sear-catches con-

5 nected therewith, an escapement-anchor also mounted on the trigger and movable therewith and means for securing one end of the escapement-anchor whereby the same is operated in the movement of the trigger, substantially as set forth.

2. In a single-trigger mechanism for firearms, the combination of the trigger, a ratchet or escapement wheel mounted upon and movable with the trigger, adjustable sear-catches connected with and temporarily secured to said ratchet-wheel, an escapement-anchor mounted upon the trigger, means for holding one end of the escapement-anchor against play and means for resetting said sear-catches, substantially as set forth.

.. The combination in a single-trigger mechanism for firearms of the single trigger, a ratchet-wheel mounted thereon having 20 catches for successively engaging the sears, an escapement-anchor mounted on the trig-

ger, means for securing one end of said escapement-anchor from oscillating movement and means for resetting said ratchet-wheel and sear-catches, substantially as set forth. 25

4. In a single-trigger mechanism for firearms, the combination of the sear, the trigger, catches for successively engaging the sears mounted on the trigger, a ratchet-wheel controlling the movement of said catches, an 30 escapement-anchor for said ratchet-wheel, a joint in said escapement-anchor and means for resetting said catches, substantially as set forth.

In witness whereof I have affixed my signature, in presence of two witnesses, this 15th day of July, 1901.

ELIJAH D. FULFORD.
